Des. 186,230
Patented Sept. 29, 1959

186,230

CHILD'S COSTUMER

Irmi Ann Gross, New York, N.Y.

Application September 18, 1957, Serial No. 47,776

Term of patent 14 years

(Cl. D33—8)

I claim:

The ornamental design for a child's costumer, substantially as shown.
